UNITED STATES PATENT OFFICE.

GUSTAVE NIEDERHEE AND WILLIAM E. LAWRENCE, OF BROOKLYN, NEW YORK.

LIMIT GOVERNOR FOR INTERNAL-COMBUSTION ENGINES.

Application filed April 17, 1924. Serial No. 707,132.

The device of the present invention contemplates the provision of a control adapted to function after the manner of a governor for restricting and regulating the fuel flow 5 to the intake manifold of the engine, whereby to prevent the engine from running beyond a predetermined speed. The device of the present invention is designed primarily for use in connection with motor trucks, 10 although without any material changes it may be used in connection with other types of motor vehicles and stationary motors.

A primary object of the invention is to provide an efficient fuel-control of simple 15 and inexpensive construction which can be quickly and conveniently incorporated, more particularly in motor truck engines, in the fuel-supply connections between the carburetor and the intake manifold of the engine.

Another object of the invention is to provide a fuel-control that is not affected in 20 any way by the usual operations of the throttle control, but which operates automatically under the suction pull exerted by the engine 25 to restrict the quantity of fuel passing to the intake and thereby to limit the speed of the engine.

According to an important feature of my invention, provision is made through the 30 employment of by-passes, controlled by gravity valves, for automatically satisfying the fuel requirements of the engine when climbing hills and upgrades.

To the attainment of the foregoing objects and advantages, the invention embodies the peculiar construction and novel arrangement of parts hereinafter described and specifically pointed out in the appended 35 claims.

An illustrated embodiment of the invention is shown in the accompanying drawing, forming a material part of this specification, and in which—

Figure 1 is a central vertical sectional view showing my improved fuel-control incorporated in the fuel-supply connections.

Fig. 2 is an underneath plan view of the device.

Figs. 3 and 4 are end and side elevations, 50 respectively, of the same.

With more particular reference to the accompanying drawing, the numeral 5 represents a fuel-supply connection leading to the intake manifold of the engine, this connection in the embodiment shown, being provided with a flange 6. 7 represents a fuel-

supply connection that leads from the carburetor and is provided with a flange 8. My invention consists of a body 9 which is interposed between the connections 5 and 7 and is secured by bolts 10 between the flanges thereof. The body 9 consists of a casting, preferably of rhomboidal shape as shown, provided through its more acute corners 11 with cored holes 12 for the reception 65 of the securing bolts 10.

Provided centrally through this casting is a circular passage 13 which is tapered or flared inwardly at 14 and is thence concentrically reduced as at 15, it being observed 70 that the larger end of this passage opens from the carburetor connection 7 while the reduced end thereof opens into the fuel-in- take connection 5. Below the inwardly- flared region 14, this passage is centrally 75 spanned by an integral bridge 16 which is centrally holed and tapped at 17 to receive the threaded portion 18 of the screw 19, in such manner that this screw extends centrally up through the inwardly-flared region 14 and 80 into the reduced passage 15, as clearly shown in Fig. 1. Underneath the bridge, there is threaded upon the screw 19 a nut 20 having its face cut with cross grooves 21 to afford 85 a choice of seats for a cotter pin 22 which is passed through the end of the screw. This arrangement provides means for normally holding the screw against turning, while providing facilities for its convenient 90 adjustment.

Slidably mounted upon the smooth portion of the screw over the bridge is a disk-shaped valve or control 23 made with an upwardly projecting hub 24. The screw, adjacent its head, is made with an annular 95 stepped up portion 25. Coiled about the stepped up portion 25 and about the hub 24 and confined between the head of the screw and the valve 23 is a push spring 26, which normally urges the valve into its extreme 100 open position upon the top of the bridge but which is sufficiently resilient to yield under the suction pull exerted by the engine so as to allow the valve to be drawn upward- 105 ly for the purpose of partially closing the cross-sectional area of the inwardly-tapered portion 14. The arrangement of the parts and the adjustment of the screw should be such that the stepped up portion 25 will 110 serve as an abutment for the hub 24 so that the passage for the fuel will never be entirely closed.

When the engine is running at low speed, the suction pull is not sufficient to raise the valve because of the urge of the spring. As the speed of the engine increases the suction becomes more powerful until a point is reached where the resistance of the spring will be overcome and the valve will be raised to a position as at 23' to restrict the quantity of fuel passing into the intake. With the 10 raising of the valve and the consequent restriction of the charges of the fuel, the speed of the engine will be reduced.

It will be understood that through proper adjustment of the screw, the engine will be 15 prevented from running beyond a predetermined speed.

When the engine is laboring under the climb of a hill or up a steep grade and the suction pull is correspondingly increased, it 20 is necessary that the quantity of fuel shall not be restricted, but that the engine shall be continuously supplied with charges of fuel sufficient to meet its requirements. To make provision for these requirements the casting 25 on either side of one of the corners 11 is preferable made with a projecting portion 27 which is inclinedly cored with a hole 28, the direction of the inclination being downwardly as best shown in Fig. 1. Each hole, 30 thus made opens directly into a by-pass 29 which provides communication between the inwardly-flared region 14 and the connection 5 leading to the intake manifold. Disposed in each of the holes 28 is a ball valve 30 which normally rolls by gravity into the by-pass the wall whereof is provided with a 35 concavity or seat 31 for the partial reception of the ball valve as shown in Fig. 1. By means of this arrangement, the by-passes are 40 normally closed against the flow of fuel into the connection 5. Now, it is to be observed that the casting is so secured between the connections 5 and 7 that the holes 28 run lengthwise of the motor truck, so that when climbing 45 a hill or steep grade, the ball valves, owing to the inclination of the motor truck, will be unseated by gravity, thereby permitting through the by-passes a free flow of the fuel into the connection 5. The outer 50 ends of the holes 28 are tapped for the reception of screw-plug closures 32.

Having thus described our invention, what we claim is:

1. A device automatically regulating the 55 volume of the gas mixture supplied to the motor of an automobile, said device being adapted to be interposed between the car-

buretor and the intake manifold of the engine and consisting of a body having a passageway tapering inwardly in its upper 60 part to end in a reduced channel, a screw adjustably supported centrally of said passageway, a spring pressed disk-shaped valve slidably mounted on said screw so as to choke the cross-sectional area of the inwardly tapered region, 65 a vertically disposed by-pass communicating with the passageway below and above the tapering portion of the same and provided in its wall with a valve seat, a slightly upwardly inclined straight channel, positioned lengthwise of the automobile with its highest closed end to the rear, and branching off the by-pass above the tapering portion, and closed at its outer end, and a gravity influenced rolling valve within the side channel 70 adapted to normally rest in its seat to close the by-pass.

2. A device automatically regulating the 75 volume of the gas mixture supplied to the motor of an automobile, said device being adapted to be interposed between the carburetor and the intake manifold of the engine and consisting of a body having a passageway tapering inwardly in its upper part to 80 end in a reduced channel, a screw adjustably supported centrally of said passageway, a spring pressed disk-shaped valve slidably mounted on said screw so as to choke the cross-sectional area of the inwardly tapered 85 region, a vertically disposed by-pass communicating with the passageway below and above the tapering portion of the same, and provided in its wall with a valve seat, a slightly upwardly inclined straight channel, 90 positioned lengthwise of the automobile with its highest closed end to the rear and branching off the by-pass above the tapering portion, and closed at its outer end, and a gravity influenced rolling valve within the side channel 95 adapted to normally rest in its seat to close the by-pass, said screw being provided with a stepped up portion at its head and said disk valve having a hub slidable on said screw and adapted to abut said stepped up portion to limit the upward movement of said disk valve when choking the fuel passage.

Signed at Brooklyn, in the county of Kings and State of New York, this first day 110 of April A. D. 1924.

GUSTAVE NIEDEREHE.
WILLIAM E. LAWRENCE.
